CLAIM

The ornamental design for a seat for chairs, stools and similar articles of furniture, as shown and described.

DESCRIPTION

FIG. 1 is a front perspective view of a seat for chairs, stools or similar articles of furniture, showing my new design, the legs of a chair being shown in broken line image only for the purpose of understanding use of the seat and forming no part of the claimed design;

FIG. 2 is a front elevational view thereof;

FIG. 3 is a left-end elevational view thereof;

FIG. 4 is a right-end elevational view thereof;

FIG. 5 is a rear elevational view thereof;

FIG. 6 is a top plan view thereof; and,

FIG. 7 is a bottom plan view thereof.
